UNITED STATES PATENT OFFICE.

HENDERSON P. CHILDRESS, OF BROOKLYN, NEW YORK.

COTTON-PICKER.

No. 800,630.

Specification of Letters Patent.

Patented Oct. 3, 1905.

Application filed May 13, 1905. Serial No. 260,251.

To all whom it may concern.

Be it known that I, HENDERSON P. CHILDRESS, a citizen of the United States, residing at Brooklyn, in the county of Kings and State of New York, have invented a new and useful Cotton-Picker, of which the following is a specification.

This invention relates more particularly to improvements in that type of cotton-picking machines disclosed in copending applications Serial Nos. 225,106, 241,690, and 244,240.

One of the principal objects is to provide novel manually-directed cotton picking and carrying means that has a wide range of movement with respect to the carrier and wherein the movable elements will not interfere with the change of position of said means.

A further object is to employ in connection with a cotton-engaging belt supporting means therefor that will keep said belt taut without regard to its change of position and to, furthermore, provide means for mounting said belt that will permit the relative movement of the different parts of the supporting means.

The preferred embodiment of the invention is illustrated in the accompanying drawings, wherein—

Figure 1 is a side elevation of a portion of a carrier-vehicle, showing one of the cotton-picking means. Fig. 2 is a plan view of the same. Fig. 3 is a vertical sectional view on an enlarged scale. Fig. 4 is a detail sectional view, on an enlarged scale, taken on the line 4 4 of Fig. 3. Fig. 5 is a cross-sectional view on the line 5 5 of Fig. 3. Fig. 6 is a vertical sectional view on the line 6 6 of Fig. 3. Fig. 7 is a view similar to Fig. 6, but showing the belt and drive pulley in section. Fig. 8 is a cross-sectional view on the line 8 8 of Fig. 3. Fig. 9 is a horizontal sectional view through the manually-directed supporting member. Fig. 10 is a detail perspective view of a pair of the hinge-ears employed for connecting the members. Fig. 11 is a detail sectional view through a modified construction of hanger member. Fig. 12 is a detail perspective view of a portion of the belt. Fig. 13 is a similar view of a slightly-modified and simpler form of belt.

Similar reference-numerals designate corresponding parts in all the figures of the drawings.

In the embodiment illustrated a portion of the carrier-vehicle is shown and is designated generally by the reference-numeral 12. Projecting therefrom is the cotton picking and

carrying means, which may be driven in any suitable manner—as, for instance, by means such as illustrated in the above-mentioned applications. Secured to the front end of the vehicle and extending in advance thereof is a pair of stationary tubular supporting members 13 and 14, held in position by a suitable bracket 15. Suspended from the outer ends of these members are hanger members, (designated, respectively, as a whole by the reference-numerals 16 and 17.) The upper ends of the hanger members are connected to the outer ends of the stationary members by hinges comprising collars 17^a, mounted on the adjacent end and having leaves 18, provided with overlapping eyes 19, through which are passed pintles 20.

The hanger members 16 and 17 preferably comprise tubular sections 21 and 22, the upper of which are provided with sleeves 23, in which the upper ends of the lower sections 22 are slidably fitted. Coiled springs 24, surrounding the sections, bridge the joints thereof and are abutted against shoulders 25, formed on the sections, said springs thus forcing the sections away from each other. Connected to the lower ends of the hanger members are manually-directed members, (designated, respectively, as a whole, by the reference-numerals 26 and 27,) the rear ends of said members and the lower ends of the hanger members being provided with hinge leaves 28, connected by pintles 29. The manually-directed members 26 and 27 comprise sections 30 and 31 in the form of tubes that are connected by tubular spring-hinge portions 32, which permit the relative lateral movement of the sections.

Mounted on a suitable driving-shaft 33 in the vehicle is a driving-pulley 34, and running upon this pulley is an endless cotton picking and carrying belt 35, one of the sides thereof being provided with a narrower section, having suitable outstanding teeth 36. In the modified structure illustrated in Fig. 13 a belt 35^a is employed, and projecting therefrom are staggered teeth 36^a. The active stretch of this belt operates through the upper or outer set of supporting members 13, 16, and 26, while the return stretch operates through the members 14, 17, and 27, said stretches thus bridging the joints between the members. It will thus be seen that the members constitute housings for the belt as well as guides for the cotton carried by said belts. In order to prevent friction and wear of the belt

at the various joints, a series of idler-pulleys are employed. Thus at the outer joint between the members 13 and 16 a pulley 37 is employed, mounted on the pintle 20, the inner face of the belt moving over this pulley. At the joint between the member 16 and the member 26 is another pulley 38, the detail structure of which is illustrated in Fig. 4. It will be seen by reference thereto that the said pulley consists of a hub 39 and outstanding annular spaced flanges 40, provided with outer guide-ribs 41. The opposite side margins of the belt operate upon the peripheral faces of the flanges of this pulley, while the teeth thereof move between the same, sufficient space being afforded between the teeth and the hub to permit the passage of cotton carried by the teeth. A doffer-brush 41^a operates against the belt contiguous to the driving-pulley 34 to remove the cotton from the belt.

At the outer free ends of the manually-directed members 26 and 27 is mounted upon brackets 42 a pulley 43, about which the belt passes, said belt thus projecting from the pulleys in order to provide a cotton picking or engaging portion. The return stretch of the belt in like manner passes over pulleys at the joints between the members, a pulley 44 being mounted on the pintle 20 at the joint between the members 14 and 17, said pulley, as illustrated in Fig. 5, consisting of spaced flanges 45, upon which the side margins of the belt operate, said flanges being spaced apart to permit the unobstructed passage of the teeth 36. On the pintle 29, that is located at the joint between the members 17 and 27, is located a pulley 46, over which the belt operates.

By reference to Figs. 3 and 9 it will be observed that the ends of the manually-directed member are arranged with their side faces substantially horizontal, passing over suitable rollers 47. In order, however, to permit the lateral flexing of the members at the joints 32, the belts are turned on edge, and for this purpose upright rollers 48 are journaled in the sections 31 contiguous to their inner ends, said rollers thus guiding the belt to upright position at the joints. Other guide-rollers 49 are located in the hanger members and in the stationary supporting members, as illustrated in Fig. 3.

In order to prevent the slipping of the driving-pulley 34 upon the belt, a friction-roller 50 is employed, which, as shown in Figs. 6 and 7, consists of a hub 51, journaled on an axle 52 and having spaced flanges 53, that bear against the side margins of the belt to hold the same in frictional engagement with the roller, said flanges permitting the passage of the teeth of the belt. The axle 52 is carried by a yoke 54, that is mounted on a stem 55, slideable in a supporting-bracket 56. A spring 57, located on the stem and interposed

between the yoke and bracket, yieldingly holds the roller 50 in its uppermost position.

The sectional structure of the hanger members may be modified—as, for instance, in the manner illustrated in Fig. 11, wherein the upper section 21^a is slightly larger in diameter than the lower section 22^a, the latter fitting within the former, and said sections being urged apart by a spring 23^a bearing against abutments 24^a, secured to the sections. 75

In actual practice a pair of the mechanisms are employed for each operator, as shown in Fig. 2, the rear sections of the manually-directed members being preferably divergently disposed and the front sections being substantially in the form of elbows and convergently disposed. Power being applied to the drive-shaft 33 in the direction illustrated by the arrow in Fig. 3, it will be evident that the upper and outer stretches of the belts will be moved rearwardly through the supporting members. The operator has only to direct the front projecting portions of the belts to and against the cotton-bolls, whereupon the teeth of said belts will disengage the cotton from said bolls, carry the same rearwardly through the supporting members, and deliver it into the vehicle. The operator may turn the front sections 31 of the manually-directed members laterally, in either direction, as indicated in dotted lines 95 in Fig. 2, or can turn the members as a whole, as also shown in dotted lines. He may, furthermore, swing the hanger and manually-directed members freely forwardly and backwardly without interference. Moreover, in any position the belts will be kept taut, as the sections of the hanger members will be yieldingly forced apart by the various springs or drawn together by the tension of the belts when turning the same in different directions. 105

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention. 110

Having thus described my invention, what I claim as new, and desire to secure by Letters Patent, is—

1. In a cotton-picker the combination with an extensible support comprising slidably-associated sections, of cotton picking and carrying means mounted therein, said sections constituting housings for said means and guides for the cotton carried thereby, and means for yieldingly urging the sections away from each other. 125

2. In a cotton-picker, the combination with an extensible support including slidably-associated housing-sections, of cotton picking and carrying means mounted on the support 130

- and including a belt that is movably mounted on the sections, is housed by said sections and bridges the joint between them, and means for yieldingly urging the sections away from each other to maintain said belt in taut condition.
3. In a cotton-picker, the combination with an extensible support including movably-associated tubular sections, of a spring for yieldingly urging the sections apart, and cotton picking and carrying means mounted on the support and including a belt located longitudinally in the sections and kept taut by the yielding spring tension upon said sections.
4. In a cotton-picker, the combination with a support including slidably-telescoped sections, of a spring yieldingly urging the sections apart, and cotton picking and carrying means mounted on the support and including a belt that is movable longitudinally of said sections and bridges the joint between them, said belt being kept taut by the yielding tension upon the sections.
5. In a cotton-picker, the combination with tubular slidably-telescoped sections, of a cotton picking and carrying belt movably passing through the sections and bridging the joint between them, a coiled spring surrounding the sections and bridging the joint between them, and abutments carried by the sections and borne against by the spring, said spring urging the sections apart and maintaining the belt in taut condition.
6. In a cotton-picker, the combination with connected relatively movable supporting members, one of said members being extensible, of means for yieldingly holding said member in extended condition, and cotton picking and carrying means mounted on the different supporting members and carrying the cotton from one to the other, said means including a belt that movably extends longitudinally of the extensible member and is held taut thereby.
7. In a cotton-picker, the combination with connected relatively movable supporting members, one of said members comprising slidably-associated sections, of a spring bearing against the sections to separate the same, and cotton picking and carrying means mounted on the different supporting members and carrying the cotton from one to the other, said means including a belt that movably extends longitudinally of the sectional member and is kept taut by the spring action thereupon.
8. In a cotton-picker, the combination with hingedly-connected members, one of said members being extensible, of means for yieldingly holding said member in extended condition, and cotton picking and carrying means including a belt extending longitudinally of the members and bridging the joint between them, said belt being held in taut condition by the said extensible member.
9. In a cotton-picker, the combination with hingedly-connected supporting members, one of said members comprising slidably-associated sections, of a spring bearing against the sections to separate the same, and cotton picking and carrying means including a belt extending longitudinally of the members and bridging the joint between them, said belt being held in taut condition by the spring action upon the sections.
10. In a cotton-picker, the combination with tubular supporting members, one of said members comprising slidably-telescoped sections, of hinges connecting the members, a spring bridging the joint between the sections of said member for urging the same apart, and an endless belt passing longitudinally through the members and bridging the joints between them and between the sections of said member.
11. In a cotton-picker, the combination with a carrier, of a stationary supporting member mounted thereon, a hanger member hinged to the supporting member and comprising slidably-associated sections, a spring for urging said sections apart, a manually-directed member hinged to the hanger member, and cotton picking and carrying means including a belt passing through the several members.
12. In a cotton-picker, the combination with a supporting member comprising hingedly-connected sections, of cotton picking and carrying means including a belt movably mounted longitudinally thereof, and means for twisting the belt upon its longitudinal axis contiguous to the joint between the sections.
13. In a cotton-picker, the combination with a supporting member comprising hingedly-connected sections, of cotton picking and carrying means including a belt movably mounted longitudinally thereof, guides for the belt carried by the different sections, and another guide for the belt located in angular relation to the other guides and contiguous to the joint between the sections for twisting said belt upon its longitudinal axis at said joint.
14. In a cotton-picker, the combination with a supporting member comprising hingedly-connected sections, of cotton picking and carrying means including a belt movably mounted longitudinally thereof, roller-guides for the belt carried by the different sections, and another roller-guide for the belt located contiguous to the joint between the sections and having its axis disposed in a plane substantially at right angles to the axis of the first-mentioned roller-guides.
15. In a cotton-picker, the combination with a supporting member comprising tubular sections, of a yielding coil connecting the adjacent ends of the sections, substantially horizontal rollers mounted on the sections, a substantially upright roller mounted contiguous to the joint between the sections, and cotton picking and carrying means including a belt having one of its faces operating against said rollers.

16. In a cotton-picker, the combination with supporting members, of a hinge connection between them, a pulley journaled on said hinge connection, and cotton picking and carrying means including a belt extending longitudinally along both members, bridging the joint between them, and passing about the pulley. 5
17. In a cotton-picker, the combination with supporting members, of hinge elements carried by the adjacent ends of the members, a pintle connecting the elements, a pulley mounted on the pintle, and a cotton-engaging belt extending longitudinally along both members, bridging the joint between them and passing about the pulley. 10
18. In a cotton-picker, the combination with tubular supporting members, of hinge-ears carried by the adjacent ends of the members, a pintle connecting the ears, a pulley mounted on the pintle, and cotton picking and carrying means mounted on the members and including a belt movable longitudinally through said members and operating over the pulley between them. 15
19. In a cotton-picker, the combination with supporting members, of a hinge connection between them, a pulley journaled on said hinge connection and having spaced annular flanges, and cotton picking and carrying means including a belt extending longitudinally along both members, bridging the joint between them, and passing about the pulley, said belt operating upon the flanges of said pulley and having cotton-engaging teeth that pass between said flanges. 20
20. In a cotton-picker, the combination with a carrier, of a supporting member mounted thereon, a hanger member, a hinge connection between the hanger member and supporting member, a pulley mounted on said hinge connection, a manually-directed member, a hinge connection between the manually-directed member and the hanger member, a pulley mounted on said latter hinge connection, and cotton picking and carrying means including a belt movable longitudinally of said members and passing about the said pulleys. 25
21. In a cotton-picker, the combination with movably-associated supporting members, of a driving-pulley, cotton picking and carrying means operatively mounted on the members and including a belt that passes about the driving-pulley, and a friction-roller operating against the belt and forcing the same into frictional engagement with the driving-pulley. 30
22. In a cotton-picker, the combination with a carrier, of a support mounted thereon and comprising movably-associated members, a driving-pulley mounted on the carrier, cotton picking and carrying means including a belt operating over the support and about the driving-pulley, a doffer-brush operating against the belt contiguous to the driving-pulley, and a spring-pressed friction-roller bearing against the belt at the driving-pulley 35
- and urging the same into engagement with said pulley. 35
23. In a cotton-picker, the combination with a carrier, of a supporting member secured thereto a hanger member, a hinge connection between the hanger and supporting members, a pulley journaled on said hinge connection, said hanger member comprising slidably-telescoped sections, a spring for urging said sections apart, a manually-directed member, a hinge connection between the manually-directed and hanger members, a pulley journaled on the hinge connection, said manually-directed member comprising sections, a yielding connection between the sections, and cotton picking and carrying means including a belt operating longitudinally of said several members and passing about the said pulleys. 70
24. In a cotton-picker, the combination with connected relatively movable supporting members, of a pulley journaled at the joint between the members and having an annular recess in its periphery, and cotton picking and conveying means including a belt that moves longitudinally on the members and passes about the pulley, said belt having cotton-engaging means that passes through the recess of the pulley. 85
25. In a cotton-picker, the combination with hingedly-connected supporting members, of a pulley journaled at the joint between the members and having an annular recess in its periphery, and cotton picking and conveying means including a belt that passes about the pulley, said belt having outstanding cotton-engaging teeth that pass through the recess of the pulley. 90
26. In a cotton-picker, the combination with cotton picking and carrying means including a driving-pulley and a cotton-carrying belt passing about the pulley and having cotton-engaging means, of an idler-roller having spaced annular flanges bearing against the marginal portions of the belt that are engaged with the driving-pulley to effect a driving frictional engagement between the belt and pulley. 105
27. In a cotton-picker, the combination with cotton picking and carrying means including a driving-pulley and a cotton-carrying belt passing about the pulley and having outstanding cotton-engaging teeth on its outer sides and between its margins, of an idler-roller having spaced annular flanges bearing against the marginal portions of the belt that are engaged with the driving-pulley to effect a driving frictional engagement between said belt and pulley, said flanges having a space between them to permit the unobstructed passage of the teeth. 115
28. In a cotton-picker, the combination with tubular members, of a hinge connection between the members, a pulley located outside the members and at the joint between them, and cotton picking and carrying means including a belt that passes through the members, 125
- 130

bridges the joint between them, and passes about the pulley.

29. In a cotton-picker, the combination with tubular members, of a hinge connection between the members, a pulley journaled on said connection and located outside and between the ends of the members, and cotton picking and conveying means mounted on the members and including a belt that passes through said members, bridges the joint between them, and passes about the pulley.

30. In a cotton-picker, cotton picking and carrying mechanism including a driving-pulley, a cotton-carrying belt passing about the pulley and having teeth on its outer side be-

tween its side margins, an idler-roller having spaced flanges bearing against the margins of the belton opposite sides of the teeth and pressing the same against the driving-pulley, said teeth passing freely between the flanges, and 20 means for yieldingly urging the idler-roller toward the driving-pulley.

In testimony that I claim the foregoing as my own I have hereto affixed my signature in the presence of two witnesses.

HENDERSON P. CHILDRESS.
